GARMENT HANGER

Henry C. Euen, Detroit, Mich., assignor, by mesne assignments, to Cleaners Hanger Company, a corporation of Michigan

Substituted for abandoned application Serial No. 123,640, February 2, 1937. This application April 7, 1942, Serial No. 438,015

2 Claims. (CL 223—87)

This invention relates to garment hangers and particularly hangers wherein a garment support and a member for hanging such support are separately formed. This application is a substitute for abandoned application Ser. No. 123,640, filed Feb. 2, 1937, and formally allowed August 8, 1938.

An object of the invention is to adapt the garment support of a garment hanger to be inexpensively blanked or stamped from light, stiff, and preferably fibrous sheet material, and to adapt a wire hanger member to be readily operatively connected to such support.

Another object is to so simplify the connection between a garment support and a wire hanger member that said parts may be delivered, disassembled, to a consignee and may be assembled by him without special machinery or skilled labor.

A further object is to provide a garment hanger whereof the garment support is well suited to carry an advertisement and is formed of a material unlikely to soil a garment.

These and various other objects are attained by the construction hereinafter described and illustrated in the accompanying drawing, wherein:

Fig. 1 is a front view of a garment hanger embodying one form of the invention.

Fig. 2 is a vertical sectional view of the same, taken on the line 2—2 of Fig. 1.

Fig. 2a is another vertical section of the hanger, taken on the line 2a—2a of Fig. 1.

Fig. 3 is a view similar to Fig. 2 but disclosing an alternative construction.

Fig. 4 is another view similar to Fig. 2, illustrating another modification.

Fig. 5 is a fragmentary perspective view of the garment support shown in Fig. 4.

Fig. 6 is a front view, partly broken away, of a hanger employing a further modification.

Fig. 7 is a vertical sectional view of the modification shown in Fig. 6, taken on the line 7—7 thereof.

In these views reference character 1 designates a board of approximate crescent shape and formed preferably as a stamping of light, stiff material such as paper box board, the upper edge thereof diverging downwardly from its center to its ends in gradual arcuate form to provide garment seats 2. The lower edge of the support is notched midway of its length, as indicated at 3.

Midway between its ends, the board 1 is engaged by the shank 4 of a wire hanger member, said shank being preferably straight except for an offset 5 formed intermediately of its length, and adapting the shank to pass through an aperture

6 in the upper portion of the board. The lower end portion of the shank is upwardly bent, as indicated at 7, in spaced relation to the shank, proper, and thus forms a U-shaped clip adapted to snugly embrace the lower central portion of the board. The upturned portion 7 is terminally bent toward the shank proper, as indicated at 8, for engagement in an aperture 9 formed in the lower portion of the board at its medial axis. The clip comprising the upward extension 7 is preferably proportioned to be placed under a spring stress as it is engaged in the described manner with the board. At a convenient distance above the board, the shank is formed with the usual supporting hook 10.

In attaching the wire hanger member to the board, the shank 4 is passed through the slot 6, as indicated by the upper dash line showing in Fig. 2, and the clip portion of the shank is disposed beneath the board, as in the lower dash line showing of said figure. The hanger member is then raised to grip the board within the clip as shown in full lines. The bent end 8 snaps into the aperture 9 when the hanger member is in final position, so that considerable resistance is offered to disengagement of the parts.

In each of its end portions, the board 1 is preferably formed with an aperture 10a and in each such aperture is engaged a hook formed on the upper end of a wire element 10b, said element depending from the board and having its lower portion hooked to engage a skirt or trousers (not shown).

In the alternative construction appearing in Fig. 3, the lower aperture 9 of the support is omitted and the upturned lower portion 7a of the shank is elongated to adapt its bent extremity 8a to snap into the aperture 6a, when the parts are assembled. In this construction, the shank does not pass through the slot 6a but is formed with a slight bend or hump 11 which projects into the slot to assist in maintaining assembly of the parts.

In both of the described constructions, the U-shaped bend of the clip is so engaged in the notch 3 of the board as to restrain the lower end of the hanger member from any lateral movement.

In the modification disclosed by Fig. 4 the board 1b is pressed to form a corrugation 12, downwardly extending from the center of its upper edge and progressively decreasing in depth, the aperture 6b opening in the lower or most shallow portion of such corrugation. The shank 4b of the wire hanger member is accommodated within the corrugation, and may hence be ex-

tended through said aperture with little, if any, offset. The upturned lower portion $7b$ of the shank $4b$ is flattened and embedded in the lower edge portion of the board $1b$, being thus fully concealed and quite rigidly attached to the support.

In the construction shown by Figs. 6 and 7, the board $1c$ substantially conforms to previous description with the exception that it is integrally formed with a tongue 13 , initially projecting upwardly from the center of the board, as indicated in dash lines in Fig. 6. By scoring this tongue at its juncture with the board, it is adapted to be downwardly bent in close proximity to the board as best appears in Fig. 7. The shank $4c$ of the wire hanger member has an upturned lower portion $7c$ substantially as heretofore described, and the bent extremity $8c$ of said portion seats substantially centrally against and bites into the tongue 13 under the spring stress imposed in applying the hanger member. Fig. 7 shows in dash lines how the shank $4c$ is initially passed through the aperture $8c$ to establish its engagement with the board $1c$.

In any of the several described forms of the invention, the garment support may be inexpensively produced from sheet material by a single stamping operation and any desired advertising may, in the same operation, be applied to said support. In shipping the disassembled parts of the hanger, they may be packaged much more compactly than would be feasible if assembly were effected at the point of shipment. The use of non-metallic material to form the garment-supporting board minimizes the likelihood of gar-

ments being soiled thereby, and its thickness is sufficient to provide a considerably larger seating surface for a garment than is afforded by the common triangular wire hanger.

5 It will be noted, in each of the described modifications of the invention, that the hanger member is passed through or set into the board at two or more points vertically spaced along the median line of the hanger to secure a rigid connection.

10 The invention is presented as including all such modifications and changes as come within the scope of the following claims.

What I claim is:

15 1. A garment hanger comprising a wire hanger member, having a hooked upper end and upturned at its lower end to form a clip, and a laterally elongated, garment-carrying member having an aperture approximately midway between its ends, affording a passage for the hanger member, and having an edge downward from such aperture, presenting a substantially horizontal portion to said clip and adapted to be embraced by the clip through an upward actuation of the hanger member, in completing the assembly, said edge being formed with a notch wherein the clip is engaged upon said upward actuation of the hanger member.

20 2. A garment hanger as set forth in claim 1, the clip having a free end portion bent toward the garment-carrying member to resist downward disengagement of the hanger member from the garment-carrying member.
